ANCHORING AND SEALING DEVICE

Jack W. Tamplen, Celina, Tex., assignor to Otis Engineering Corporation, Dallas, Tex., a corporation of Delaware

Filed Apr. 6, 1960, Ser. No. 20,480

12 Claims. (Cl. 166—185)

This invention relates to well tools and more particularly to a well tool system employing anchoring and sealing devices and to anchoring and sealing devices.

An object of this invention is to provide a new and improved well tool assembly having anchoring and sealing devices for anchoring the well tool assembly in a well flow conductor and sealing with the well flow conductor above and below a lateral port of the well flow conductor.

Another object is to provide a well tool assembly positionable in a well flow conductor and having anchoring and sealing devices for anchoring the well tool assembly in the well flow conductor and sealing above and below a lateral port of the well flow conductor wherein the anchoring and sealing devices are operable by a downward force imparted to the well tool assembly by means of a flexible line by which the well tool assembly is lowered into the well flow conductor.

Still another object is to provide a well tool assembly having a gas lift valve and having anchoring and sealing devices disposed on opposite sides of the gas lift valve for anchoring the well tool assembly in a well flow conductor and sealing with the well flow conductor above and below a lateral port of the well flow conductor whereby gas flowing into the well flow conductor through the port is constrained to flow through the gas lift valve.

A further object of the invention is to provide a well tool assembly having a pair of longitudinally spaced anchoring and sealing devices for sealing above and below a lateral port of a well flow conductor wherein the fluid pressure exerted through the lateral port of the well flow conductor tends to hold the anchoring and sealing devices in operative anchoring and sealing positions.

A still further object is to provide a well tool assembly having a pair of spaced anchoring and sealing devices for anchoring the well tool assembly in a well flow conductor and sealing above and below a lateral port of the well flow conductor wherein the anchoring and sealing devices each include a sealing means and an expander means movable relative to the sealing means for expanding the sealing means into engagement with the well flow conductor to anchor the well tool assembly in the well flow conductor and simultaneously seal between the well tool assembly and the well flow conductor.

A still further object is to provide a well tool assembly having a pair of spaced anchoring and sealing devices for anchoring the well tool assembly in a well flow conductor and sealing above and below a lateral port of the well flow conductor wherein the anchoring and sealing devices each include a sealing means and an expander means movable relative to the sealing means for expanding the sealing means into engagement with the well flow conductor to anchor the well tool assembly in the well flow conductor and simultaneously seal between the well tool assembly and the well flow conductor, the expander having piston means exposed to the pressure of the fluid from exteriorly of the well flow conductor whereby the pressure of the fluid tends to force the expander means into

2

engagement with the sealing means and to increase the force holding the anchoring and sealing means in anchoring and sealing positions.

Another further object is to provide a well tool assembly having a pair of spaced anchoring and sealing devices for anchoring the well tool assembly in a well flow conductor and sealing above and below a lateral port of the well flow conductor wherein the anchoring and sealing devices each include a sealing means and an expander means movable relative to the sealing means for expanding the sealing means into engagement with the well flow conductor to anchor the well tool assembly in the well flow conductor and simultaneously seal between the well tool assembly and the well flow conductor, wherein the expander means is provided with a plurality of piston means each exposed to the pressure of the fluid from exteriorly of the well flow conductor whereby the force exerted on the expander means tending to move them into the seal means expanding position is compounded without increasing the cross-sectional area of the individual piston means.

Another object is to provide a new and improved anchoring and sealing device having an expansible sealing means and an expander longitudinally movable relative to the sealing device to expand the latter and move it into anchoring and sealing engagement with a well flow conductor when the anchoring and sealing device is disposed in a well flow conductor.

Still another object is to provide an anchoring and sealing device having expandable seal means and an expander wherein the expander is provided with pressure responsive means exposable to fluid pressure for moving the expander member toward seal means expanding position.

35 A further object is to provide an anchoring and sealing device having an expandable seal means and an expander movable relative to the seal means for expanding the seal means into anchoring and sealing position, the expander having piston means exposable to fluid pressure for moving the expander toward the seal means expanding position whereby the force holding the expander in seal means expanding position varies in accordance with the fluid pressure.

40 A still further object is to provide a new and improved anchoring and sealing device having an expansible seal means and an expander movable longitudinally relative to the seal means for expanding the seal means into anchoring and sealing engagement with a well flow conductor wherein the expander is provided with pressure responsive means exposed to the fluid pressure within the well flow conductor which tends to move the expander member toward the seal means expanding position whereby the force tending to hold the expansible anchoring and sealing means in anchoring and sealing engagement varies directly with the fluid pressure within the well flow conductor.

45 A still further object is to provide a new and improved anchoring and sealing device having an expansible seal means and an expander movable longitudinally relative to the seal means for expanding the seal means into anchoring and sealing engagement with a well flow conductor wherein the pressure sensitive means comprises a plurality of piston means each exposed to the pressure of the fluid within the well flow conductor whereby the effective force of the fluid pressure tending to hold the

sealing means in expanded anchoring and sealing position is compounded in accordance with the number of piston means provided.

Additional objects and advantages of the invention will be readily apparent from the reading of the following description of a device constructed in accordance with the invention, and reference to the accompanying drawings thereof, wherein:

FIGURE 1 is a vertical view of the well tool assembly embodying the invention installed in a well flow conductor or tubing string within the casing of a well;

FIGURE 2 is a vertical sectional view of one of the anchoring and sealing devices employed in the well tool assembly illustrated in FIGURE 1;

FIGURES 3 and 4 are cross sectional views taken on lines 3-3 and 4-4 respectively of FIGURE 2; and

FIGURE 5 is a vertical sectional view of a modified form of the anchoring and sealing device.

Referring now particularly to FIGURE 1 of the drawing, the well tool assembly 10 is shown disposed in a well flow conductor or tubing string 11 disposed within the casing 12 of a well. The well flow conductor 11 is formed of tubing sections 13 whose adjacent ends are connected by coupling collars 14 in the usual manner. The upper tubing section 13 is provided with a plurality of lateral ports 16 communicating the interior of the tubing string with the cylindrical flow passage 17 formed between the tubing string and the well casing. A packer 20 seals between the tubing string and the well casing below the lateral ports whereby lift gas introduced under pressure at the surface into the cylindrical passage may pass downwardly through the cylindrical passage and then through the lateral ports 16 into the tubing string or well flow conductor.

The well tool assembly 10 includes a pair of longitudinally spaced anchoring and sealing devices 22a and 22b, identical in structure, which are disposed on opposite sides of the lateral ports 16 of the well flow conductor whereby the gas flowing into the well flow conductor through the lateral ports cannot pass either downwardly or upwardly between the anchoring and sealing devices and the internal wall surfaces of the well flow conductor, but must flow through the lateral ports 24 of the gas lift valve 25 connected to and between the anchoring and sealing devices 22 by means of the couplings 26. The gas lift valve may be of the type shown in the patent to Cummings, 2,642,889, which operates in the manner set forth in the patent to Cummings to cause the gas entering into the gas lift valve to lift the well fluids to the surface.

The well tool assembly is positioned in the appropriate location relative to the lateral ports 16 of the well flow conductor 11 by the collar stop 28 which is anchored at the collar recess 29 by means of the bosses 30a of the collet fingers 30 thereof. The collar stop may be of the type illustrated in Figure 54 on page 4151 of the Composite Catalog of Oil Field Equipment and Services, 1957-58 edition.

The collar stop, the anchoring and sealing devices, and the gas lift valves are provided with communicating longitudinal flow passages whereby the well fluids from below the well tool assembly may flow upwardly through the collar stop and through the well tool assembly past the anchoring and sealing devices 22 and thence to the surface. The lifting gas is introduced into such continuous flow passage through the gas lift valve.

Each of the anchoring and sealing devices 22 includes a tubular mandrel or body 31 having a lower section 31a, a connector section 32 threaded into the upper end of the lower section, a cap section 33 threaded on the upper end of a connector section and a resilient anchoring and sealing element 34 whose lower end is telescoped into the upper portions of the cap section and is bonded thereto. The cap section has an enlarged bore at its upper end which provides an annular outwardly and upwardly ex-

tending shoulder or surface which abuts the outer surface of the lower portion of the sealing element 34 and an upwardly facing annular shoulder 36 which abuts the lower end of the element 34. The connecting section 32 of the mandrel has an upper portion of reduced external diameter which provides an upwardly facing annular shoulder 38 adapted to engage the lower end of the anchoring and sealing element 34 and an annular surface 39 which engages the internal end portion surface of the lower portion of the resilient element 34. The lower end portion of the sealing element is thus held between the surfaces 35 and 39 of the cap section and the connector section as well as being bonded to the cap section.

The connector section is enlarged intermediate its ends to provide an upwardly facing shoulder 40 engageable with the lower end of the cap section 33 to limit longitudinal movement of the connector section relative to the cap section and position the upwardly facing shoulders 36 and 38 of the cap section and the connector section in alignment wherein both are in engagement with the lower end of the resilient sealing element 34.

The lower section 31a has lateral ports 42 immediately below the lower end of the connector section whereby fluid pressure may enter into the interior of the mandrel from exteriorly thereof. The lower end of the lower section 31a of the mandrel is reduced and provided with external threads whereby it may be connected to other well tools, such as the gas lift valve 25, by means of a coupling or collar 26.

The resilient sealing element 34 is expandable outwardly into anchoring and sealing engagement with the internal wall surface of a tubing section 13 by an expander member 45 having an upper expander section 46 and a lower piston section 47 threadedly connected to the lower end of the expander section. The expander section has an external flange 49 at its upper end providing an undercut downwardly facing shoulder 50 which is engageable by running and pulling tools. The expander section has an enlarged lower portion providing an upper downwardly and inwardly extending surface 52, an intermediate cylindrical surface 53 and a lower downwardly and inwardly inclined expanding surface 54 which extends substantially parallel to the upwardly and outwardly inclined surface 35 of the cap section 33 of the mandrel 31. The resilient anchoring and sealing element 34 is provided with internal annular surfaces 56, 57, and 58 which correspond in configuration to the surfaces 52, 53 and 54 of the expander section, but which are of smaller internal diameter than the external diameter of the corresponding surfaces of the expander section so that the expander section expands the portions of the resilient sealing element and compresses them against the internal surface of the tubing section 13 when the expander member 45 is moved downwardly from an upper position, wherein the cylindrical surface 53 of the expander section is disposed above and out of engagement with the intermediate internal cylindrical surface 57 of the resilient sealing element, to the expanding and compressing position illustrated in FIGURE 2, wherein the exterior surfaces 52, 53, and 54 of the expander section are in engagement with the internal surfaces 56, 57, and 58, respectively of the sealing element.

The piston section 47 of the expander member is provided with vent ports 60 which open outwardly below the lower end of the expander section 46 whereby any fluid between the expander section and the resilient sealing element 34 may escape into the bore or passage of the tubular piston section upon movement of the expander section into the resilient sealing device.

The lower end of the piston section 47 is provided with an external piston means or flange 62 having an external annular recess or groove 63 in which is disposed a suitable sealing means 64, such as an O-ring,

which engages the internal wall surfaces of the lower mandrel section 31a below the lateral port 42. The connector section has a similar internal annular recess or groove 66 in which is disposed a sealing means 67, such as an O-ring which seals between the connecting sub and the piston section above the lateral port. A suitable sealing means or O-ring 68a is disposed between the lower end of the cap section and the upper end of the lower section of the mandrel to engage and seal therebetween and also to engage and seal with the outer surface of the connector section 32.

It will now be apparent that the pressure of any fluid flowing through the lateral ports 42 of the lower section 31a of the mandrel 31 into the chamber 69 between the lower end of the connector section and the piston flange will act upon the upper annular surface 68 of the piston flange 62 to move the expander member 45 into the resilient sealing element of the mandrel 31 to cause it to expand and move into anchoring and sealing engagement with the internal wall surface of the tubing section 13. The pressure of the fluid in the tubing string exteriorly of the outer mandrel will thus tend to move the expander member into the outer mandrel and increase the force with which the resilient sealing element 34 is held in engagement with the tubing section so that the greater the force which might tend to cause fluid to flow between the sealing element 34 and the tubing string, the greater will be the force tending to expand the sealing element into sealing and anchoring engagement with the tubing string.

The anchoring and sealing devices 22a and 22b are identical in construction with the lower anchoring and sealing device 22b being reversed longitudinally whereby the expansion of the resilient sealing element 34 of the anchoring and sealing device 22b is effected by movement of the sealing element 34 downward relative to the expander section 45 whereas the expansion of the sealing element 34 of the upper anchoring and sealing device 22a is effected by downward movement of the expander 45 relative to the sealing element thereof.

In use, when it is desired to locate the well tool assembly 10, which includes a pair of the anchoring and sealing devices connected to opposite ends of the gas lift valve 25, in such position in the tubing section 11 that the anchoring and sealing devices are disposed on opposite sides of the lateral apertures or ports 16 of the tubing section 13 and in sealing and anchoring engagement with the tubing section above and below the lateral apertures 16 so that any gas pumped into the annular passageway 17 between the tubing section and the well casing 12 will be caused to flow through the ports 24 of the gas lift valve 25 and thence through the gas lift valve and through the upper anchoring and sealing device to the tubing string above the well tool assembly and thence to the surface, the collar stop 28 is first positioned in the tubing string at the collar recess 29 at the lower end of the tubing section 13 provided with the lateral ports 16.

The well tool assembly is then connected to a flexible line by means of a suitable running tool and the usual set of flexible line equipment and lowered thereby into the tubing string 11. Since the running tool is connected to the upper end of the expander member 45 of the upper anchoring and sealing device 22a, the mandrel 31 thereof is held in a lower position relative to the expander member 45 by the weight of the other elements of the well tool assembly, the upper surface 68 of piston flange 62 engaging the lower end of the connector section 32 to limit downward movement of the mandrel relative to the expander member. The sealing element 34 is therefore in its contracted condition since the expander section is not in expanding engagement therewith.

The expander member 45 of the lower anchoring and sealing device 22b is suspended from the outer mandrel 31 thereof by the engagement of the surface 68 of the

piston flange 62, which of course is downwardly facing, with the upper end of its connector section 32 so that the resilient anchoring and sealing device element 34 is in its contracted position and out of engagement with the walls of the well tubing.

The well tool assembly 10 is lowered into the tubing string until the lower end of the expander member 45 of the lower anchoring and sealing device engages the collar stop which thus locates the well tool assembly in proper position relative to the lateral ports 16 of the tubing string with the two anchoring and sealing devices positioned above and below the lateral ports 16 of the tubing section 13. The expander member 45 and the resilient sealing element 34 of the lower anchoring and sealing device 22b move longitudinally relative to one another whereby the resilient sealing element 34 of the lower anchoring and sealing device 22b is expanded into engagement with the internal walls of the tubing string.

Downward jars are then imparted by means of the flexible line to the running tool and to the expander member 45 of the upper anchoring and sealing device 22a to cause the expander members of both the upper and lower anchoring and sealing devices to move inwardly relative to their mandrels 31 to expand the anchoring and sealing elements 34 thereof into anchoring and sealing engagement with the tubing. The running tool is then disengaged from the upper end of the expander member 45 of the upper anchoring and sealing device and removed from the well.

30 A lift gas, such as air, is then forced downwardly under pressure into the inner annulus or passageway 17 between the well casing and the tubing string and through the aperture 16 into the chamber 72 of the well tubing formed between the expanded sealing elements 34 of the anchoring and sealing devices. The gas under pressure flows inwardly through the ports 24 of the gas lift valve to mingle with the well fluids flowing through the collar stop and through the longitudinal bore of the anchoring and sealing device 22a to aid in lifting the well fluids to the surface. Simultaneously the fluid under pressure enters through the ports 42 of the outer mandrels 31 of the upper and lower anchoring and sealing devices and exerts a force on the expander members 45 thereof which tends to cause the expander members 45 to move further inwardly relative to and further expand the resilient seal elements 34 thereof thereby causing the well tool assembly to be more securely locked in the well tubing. The pressure in the well tubing below the well tool assembly is of course smaller than the pressure of the lift gas being introduced into the annulus 17 and therefore the chamber 72. It will thus be seen that whenever the pressure of the lift gas increases, which might tend to cause the gas to flow or leak between the sealing elements and the well tubing, the force acting on the piston flanges 62 also increases to exert a greater expanding force on the resilient seal elements and thus prevents any such leakage.

When it is desired to remove the well tool assembly from the well, the annular space is opened to the atmosphere at the surface to relieve the pressure acting on the piston flanges of the anchoring and sealing devices which tends to cause the expander members to hold the anchoring and sealing elements 34 in their operative anchoring and sealing positions in the tubing string. A suitable pulling tool, such as the Otis type R pulling tool illustrated in Figure 67, page 4159 of the Composite Catalog of Oil Field Equipment and Services, 1957-58 edition, is then lowered into the well tubing by means of a flexible line until its dogs engage the undercut shoulder 50 at the upper end of the expander member 45 of the upper anchoring and sealing device. Upward movement of the pulling tool then causes the expander member 45 of the upper anchoring and sealing device to move upwardly relative to its resilient sealing element and out of expanding engagement therewith until the piston flange thereof engages the lower

end of the connector section. The sealing element thus is freed to contract and move out of anchoring and sealing engagement with the tubing section 13. Further upward movement imparted to the well tool assembly then causes the mandrel 30 of the upper anchoring and sealing device 22a, the well tool 25 and the mandrel 30 of the lower anchoring and sealing device 22 to move upwardly thereby causing relative movement between the sealing element 34 of the lower anchoring and sealing device and its expander member 45 whereby the expander member is placed out of expanding engagement with the internal surfaces of the resilient sealing element 34, permitting the sealing element to contract to retracted position out of anchoring and sealing engagement with the tubing section. The mandrel of the lower anchoring and sealing device moves upwardly relative to the expander member thereof until the shoulder 68 of the piston flange 62 thereof engages the adjacent end of the connector section 32 thereof. The expander member 45 of the lower anchoring and sealing device will then move upwardly with the well tool assembly as it is moved upwardly through the tubing for removal from the tubing string.

The collar stop 28 may then be removed from the tubing string if so desired or may be left in position for use in further operation of the well.

It will be apparent that the collar stop 28 may be connected to the lower end of the expander member 45 of the lower anchoring and sealing device whereby it can be lowered into the tubing string and removed therefrom simultaneously with the lowering and removal of the well tool assembly 10 into and from the tubing string.

It will further be apparent that while a particular gas lift valve has been illustrated as being connected between the upper and lower anchoring and sealing devices of the well tool assembly, that any desired well device may be connected there between.

It will be now seen that a new and improved well tool assembly has been illustrated and described which includes a well tool or device 25 to whose opposite ends are secured anchoring and sealing devices 22 adapted to seal between the well tool assembly and a well flow conductor in which the well tool assembly is located and above and below such well tool or device.

It will further be seen that the well tool assembly may be easily lowered, operated and removed from a well flow conductor by means of a flexible line and that the well tool assembly may be anchored in anchoring and sealing position and removed from such anchoring and sealing position by downward or upward jars imparted to the well tool assembly by means of the flexible line.

It will further be seen that the anchoring and sealing devices of the well tool assembly are provided with pressure responsive means exposed to the fluid pressure within the well flow conductor between the anchoring and sealing devices which increases the force tending to force the anchoring and sealing devices into anchoring and sealing engagement with the well flow conductor whenever the fluid pressure within the well flow conductor between the anchoring and sealing devices increases.

It will further be seen that a new and improved anchoring and sealing device has been illustrated and described which includes an outer tubular mandrel or body 31 having a tubular resilient expandable anchoring and sealing element on one end thereof and an expander member 45 longitudinally movable relative to the mandrel and movable into engagement with the resilient anchoring and sealing element upon its movement in one direction relative to the mandrel to expand the resilient element into anchoring and sealing position or engagement with a well flow conductor in which the anchoring and sealing device is disposed.

It will further be seen that the mandrel of the anchoring and sealing device has the resilient anchoring and sealing means extending from one end thereof and that the

other end of the mandrel is connectable to any desired well tool.

In FIGURE 5 is illustrated a modified form of the anchoring and sealing device illustrated in FIGURES 1 through 4. The anchoring and sealing device 100 includes an outer tubular mandrel or body 102 having a resilient anchoring and sealing element 104 at one end thereof secured between the upper ends of the cap section 105 and a connector section 106 in the same manner as the resilient anchoring and sealing element 34 of the anchoring and sealing device 22 is secured by the identically formed cap section 33 and connector section 32 thereof.

An intermediate mandrel section 107 is threaded on the lower end of the connector section 106 and has a lower portion of reduced internal diameter provided with an internal recess 109 in which is disposed a sealing means 110 which may be of any suitable type, such as an O-ring. A lower mandrel section 112 is threaded on the lower end portion of the intermediate mandrel section and has a reduced externally threaded portion 114 to which may be connected a well tool, such as the valve 25, by means of the coupling or collar 26. The intermediate mandrel section is provided with lateral ports 116 disposed immediately below the connector section 107 and the lower mandrel section 112 is provided with lateral apertures or ports 117 disposed immediately below the lower end of the intermediate section 107.

The expander member has an upper section 121 which is identical with the expander section 46 of the anchoring and sealing device of FIGURES 1 through 4 and has a flange 122 on the upper end thereof providing an undercut annular shoulder 123 engageable by running and pulling tools. The expander section 121 is enlarged adjacent its lower end portions to provide an inwardly and downwardly extending annular surface 124, a cylindrical surface 125 and a downwardly and inwardly inclined surface 126 which engage the internal surfaces 128, 129 and 130, respectively, of the sealing element 104 to expand the sealing element into anchoring and sealing engagement with the internal wall surfaces of a tubing section 13 of a tubing string or well flow conductor T.

The expander member 120 has an intermediate piston section 133 having an upper end threaded into the lower end of the expander section 121 and a lower end provided with an external piston flange 135. The piston flange is provided with an external annular recess 136 in which is disposed an O-ring 137 or other suitable sealing means which seals between the internal wall surfaces of the intermediate mandrel section 107 and the piston flange. A lower piston section 138 has an upper end threaded into the lower end of the intermediate piston section and is provided at its lower end with a piston flange 140 having an external annular recess 141 in which is disposed an O-ring 142 or other suitable sealing element which engages the internal wall surfaces of the lower mandrel section 112.

The lower mandrel section has a vent port 150 disposed immediately below the end of the piston flange 135 of the intermediate piston section whereby any fluids 60 trapped below the piston flange 135 and above the internal upwardly facing shoulder 152 of the intermediate mandrel section may flow into the longitudinal bore of the expander member when the expander member moves longitudinally in the outer mandrel toward an operative 65 position wherein it engages and expands the sealing element 104. The port 150 of course also permits flow of fluids into the space between the piston flange 135 and the shoulder 152 of the intermediate mandrel section when the expander moves in opposite direction.

The connector section 106 has an internal annular recess 153 in which is disposed an O-ring 154 or other suitable sealing means for sealing between the intermediate piston section and the connector section.

It will now be apparent that the anchoring and sealing device 100 functions in exactly the same manner as the

anchoring and sealing devices 22 illustrated in FIGURES 1 through 4 except that the provision of the pair of longitudinally spaced piston flanges 135 and 140 multiplies or compounds the force exerted by the fluid pressure externally of the mandrel which enters both into the piston chamber 155 formed between the connector section 106 and the piston flange 135 of the intermediate piston section 133 to exert a force on the piston flange 135 and into the chamber 156 formed between the lower end of the intermediate section and the upper end of the piston flange 140 to exert a force on the piston flange 140 tending to cause the expander member to move into expanding engagement with the sealing element 164. It will thus be apparent that the provision of a pair of piston flanges 135 and 140 effectively multiplies the area of the piston means of the expander member which is exposed to the fluid pressure which tends to move the expander member into expanding engagement with the anchoring and sealing means 104.

It will now be seen that a new and improved anchoring and sealing device which may be used in the same manner as the anchoring and sealing devices 22 illustrated in FIGURES 1 through 4 has been illustrated and described and includes an outer mandrel connectable at one end with any suitable well device and provided at the other end with a tubular resilient expandable sealing means 104 which is movable toward expanded position by an expander member 120 longitudinally movable in the mandrel 102 and having a plurality of piston means engageable with the outer mandrel and exposed to the pressure of the fluids exteriorly of the mandrel which exert a force on the piston means for moving the piston member toward expanding engagement with the anchoring and sealing means of the outer mandrel.

It will further be seen that although the expander member 120 has been provided with only a pair of piston flanges, it will be apparent that any desired number of such piston flanges may be provided, in which event an additional intermediate mandrel, such as the mandrel section 107, would be provided between the connector section 106 and the lower mandrel section 112 of the mandrel for each said additional piston flange.

It will now be further seen that the provision of a plurality of piston flanges causes a small increase in the pressure of the fluid in the passage or compartment 164 of the tubing string to cause a large increase in the force tending to move the expander member toward expanding engagement with the anchoring and sealing element 104.

The anchoring and sealing device 100 of course may be connected in a well tool assembly in exactly the same manner as the anchoring and sealing devices 22 and located and anchored in a tubing string and removed therefrom in the same manner as the anchoring and sealing devices 22 illustrated in FIGURES 1 through 4.

If desired the expander members of the anchoring and sealing devices 100 may be moved from their sealing means expanding positions in their mandrels 102 by introducing pressure into the tubing string at the surface while opening to the atmosphere the annular passageway 17 between the tubing string and the well casing so that the fluid pressure entering through the ports 150 of the low piston sections 138 exerts a force on piston flanges 135 of the intermediate piston sections 133 which moves the expander member outwardly of the mandrel and out of expanding engagement with the sealing elements 104. In this event the flexible line and pulling tool would merely remove the well tool assembly employing these anchoring and sealing devices and would not have to move the expander members out of engagement with the sealing elements.

The foregoing description of the invention is explanatory only, and changes in the details of the construction illustrated may be made by those skilled in the art, within the

scope of the appended claims, without departing from the spirit of the invention.

What is claimed and desired to be secured by Letters Patent is:

- 5 1. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having a tubular expandable means and an expander telescopic inwardly relative to the expandable means and engageable therewith for expanding said expandable means into anchoring and sealing engagement with the well flow conductor, said expanders of said anchoring and sealing devices being longitudinally movable in opposite directions toward expanding engagement with their associated expandable means; and fluid pressure piston and cylinder means on said anchoring and sealing devices and having communication with the exterior of said devices for conducting fluid pressure to said piston and cylinder means for moving said expanders longitudinally into expanding engagement with their associated expandable means.
- 10 2. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having a tubular expandable means and an expander telescopic inwardly relative to the expandable means and engageable therewith for expanding said expandable means into anchoring and sealing engagement with the well flow conductor, piston and cylinder means connected with said expander and said expandable means and having communication with the exterior of said anchoring and sealing device for conducting fluid pressure from exteriorly of said device to said piston and cylinder means to move said expander longitudinally to telescope into and expand said expandable means to effect a seal between said well tool and said well flow conductor, said well tool assembly having a longitudinal passageway therethrough, said well tool providing for flow of fluid from said lateral port into said longitudinal passageway, said expanders of said anchoring and sealing devices being longitudinally movable in opposite directions toward expanding engagement with said expandable means.
- 15 3. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having a tubular expandable means and an expander telescopic inwardly relative to the expandable means and engageable therewith for expanding said expandable means into anchoring and sealing engagement with the well flow conductor, said expanders of said anchoring and sealing devices extending outwardly in opposite directions from their associated expandable means and said well device whereby one of said expander members may be secured to a flexible line for movement thereby through the well flow conductor.
- 20 4. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having a tubular expandable means and an expander telescopic inwardly relative to the expandable means and engageable therewith for expanding said expandable means into anchoring and sealing engagement with the well flow conductor, said expanders of said anchoring and sealing devices being longitudinally movable in opposite directions toward expanding engagement with their associated expandable means.

able means and an expander telescopic inwardly relative to the expandable means and engageable therewith for expanding said expandable means into anchoring and sealing engagement with the well flow conductor, said well tool assembly having a longitudinal passageway therethrough, said well tool providing for flow of fluid from said lateral port into said longitudinal passageway, said expanders of said anchoring and sealing devices extending outwardly in opposite directions from their associated expandable means and said well device whereby one of said expanders may be secured to a flexible line for movement thereby through a well flow conductor.

5. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having a tubular expandable means and an expander telescopic inwardly relative to the expandable means and engageable therewith for expanding said expandable means into anchoring and sealing engagement with the well flow conductor, said expanders of said anchoring and sealing devices being longitudinally movable in opposite directions toward expanding engagement with said expandable means thereof, said expanders of said anchoring and sealing devices extending outwardly in opposite directions from their associated expandable means and said well device whereby one of said expanders may be secured to a flexible line for movement thereby through a well flow conductor.

6. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having an expandable means and an expander movable relative to the expandable means and engageable therewith for expanding said expandable means into anchoring and sealing engagement with the well flow conductor, said expanders being provided with means responsive to the fluid pressure within said well flow conductor for exerting forces on said expanders tending to move the expanders into expanding engagement with said expandable means, said anchoring and sealing devices each including a mandrel, said expandable means being carried by said mandrel, said pressure responsive means including piston means on said expander movable in said mandrel, said mandrel being provided with aperture providing fluid flow communication between the interior of the well flow conductor and the interior of said mandrel for exposing said piston means to fluid pressure from the interior of said well flow conductor to move said expander.

7. A well tool assembly positionable in a well flow conductor having a lateral port, including: a well tool; and a pair of anchoring and sealing devices connected to said well tool at opposite ends of said well tool, said well tool assembly being positionable in the well flow conductor with said anchoring and sealing devices disposed on opposite sides of said lateral port, each of said anchoring and sealing devices having an expandable means and an expander engageable therewith for expanding said expandable means into anchoring and sealing engagement with the well flow conductor, said expanders being provided with means responsive to the fluid pressure within said well flow conductor for exerting forces on said expanders tending to move the expanders into expanding engagement with said expandable means, said anchoring and sealing devices each including a mandrel, said expandable means being carried by said mandrel, said pressure responsive means including a plurality of spaced piston means on each expander, said mandrel being provided with

apertures providing fluid flow communication between the interior of the well flow conductor and the interior of said mandrel for exposing said piston means to fluid pressure from the interior of the well flow conductor.

8. A well tool including: a mandrel having a passageway and a lateral port communicating exterior of the mandrel with the passageway; an expandable member carried by said mandrel; and an expander movably carried by said mandrel and engageable with said expandable member when moved in one direction relative to said mandrel for expanding said expandable member; and piston means on said expander exposed to fluid pressure from exterior of the mandrel through said lateral port and responsive to said fluid pressure to move said expander in said one direction.

9. A well tool including: a mandrel having a longitudinal passage and a plurality of longitudinally spaced lateral ports communicating the exterior of the mandrel with said passageway; an expandable member carried by said mandrel; and an expander movable longitudinally relative to said mandrel and engageable with said expandable member for expanding said member when moved in one longitudinal direction relative to said expandable member, said expander being provided with a plurality of longitudinally spaced separate piston and cylinder means each exposed to the fluid pressure from the exterior of the mandrel through an associated one of said plurality of lateral ports, said fluid pressure exerting from exterior of the mandrel a force on each of said piston and cylinder means tending to move said expander in said one direction.

10. A well tool including: a mandrel having a longitudinal passageway and a lateral port communicating the exterior of the mandrel with the passageway; an expandable member carried by said mandrel on one end thereof; and an expander longitudinally movable in said passage of said mandrel and engageable with said expandable member for expanding said expandable member upon movement of said expander in one longitudinal direction in said passageway, said mandrel and said expander having cooperable means providing a chamber communicating with said lateral port, said expander having piston means disposed in said chamber whereby fluid pressure from exterior of said mandrel exerts a force through said lateral port on said piston means of said expander tending to move said expander in said one direction.

11. A well tool including: a mandrel having a longitudinal passageway and a lateral port communicating the exterior of the mandrel with the passageway; an expandable member carried by said mandrel on one end thereof; and an expander longitudinally movable in said passage of said mandrel and engageable with said expandable member for expanding said expandable member upon movement of said expander in one longitudinal direction in said passageway, said mandrel and said expander having cooperable means providing a chamber communicating with said lateral port whereby fluid pressure from exterior of said mandrel exerts a force through said lateral port of said expander tending to move said expander in said one direction, said cooperable means comprising an annular external flange on said expander member and a downwardly facing annular shoulder on said mandrel said flange and said shoulder being disposed on opposite sides of said lateral port, and sealing means between said mandrel and said expander above said lateral port and between said mandrel and said external flange below said lateral port.

12. A well tool including: a mandrel having a longitudinal passageway and a plurality of longitudinally spaced lateral ports communicating with the exterior of the mandrel with the interior of said passageway; an expandable member carried by said mandrel on one end thereof; and an expander movable in said passageway and engageable with said expandable member upon movement of said expander member in one longitudinal direction relative to said mandrel; and cooperable means

13

on said mandrel and said expander and exposed to fluid pressure responsive to the pressure from exterior of the mandrel through said lateral ports for moving said expander in said one direction, said cooperable means including a plurality of longitudinally spaced external flanges on said expander member and longitudinally spaced internal annular shoulders on said mandrel disposed above and below each of said ports, each of said external flanges of said expander member being disposed between a pair of said internal annular shoulders, seal-

5

ing means between said mandrel and said expander above each of said ports and sealing means between said external flanges and said mandrel below said ports.
